CENTRIFUGAL PUMP MECHANISM

Victor N. Albertson, Minneapolis, Minn.

Application May 27, 1942, Serial No. 444,616

9 Claims. (Cl. 103—103)

This application is filed as a continuation-in-part of my pending application Serial No. 392,267 filed May 7, 1941, under title "Auto parts washer," and which application matured into Patent No. 2,352,356 on June 27, 1944. The present invention is directed to an improved centrifugal pump mechanism and associated filter; and, generally stated, consists of the novel devices, combinations of devices, and arrangement of parts hereinafter described and defined in the claims.

The invention is illustrated in the accompanying drawings wherein like characters indicate like parts throughout the several views.

Referring to the drawings:

Fig. 1 is a transverse vertical section taken through the washing apparatus such as that disclosed in my pending application above identified and showing the improved pump and filter mechanism incorporated in the said washing machine;

Fig. 2 is a longitudinal section taken approximately on the line 2—2 of Fig. 1;

Fig. 3 is an axial section taken through the pump and filter mechanism substantially on the line 3—3 of Fig. 1;

Fig. 4 is a transverse section taken on the line 4—4 of Fig. 3;

Fig. 5 is a view in elevation, with some parts broken away, illustrating a centrifugal pump head that differs slightly in details of construction from that shown in Fig. 3; and

Fig. 6 is a view, partly in plan and partly in axial section, taken on the line 6—6 of Fig. 5.

Referring first to the construction illustrated in Figs. 1 to 4, inclusive, Figs. 1 and 2 illustrate substantially the same use of the pump and filter mechanism herein claimed applied to a washing machine of the type of my above identified pending application, and hence, the parts of the washing apparatus, other than of the pump and filter mechanism, will be quite briefly described as follows: The tank for containing the washing fluid, here illustrated, is a rectangular structure 10, preferably formed of sheet metal, provided at a point considerably below the open top thereof with a work table or deck 11. At one end of the tank and separated from the interior thereof is a box-like motor housing 12. This motor housing is, by suitable means, securely anchored to and obliquely projects into the tank 10 below the deck 11.

The tank 10 along its sides and ends is provided with a sediment receiving trough 13. Within the motor housing 12 is an electric motor, not herein shown but illustrated in my pending application, the rotor of which is provided with an obliquely

extended shaft 14 that extends into a drum-like shell or casing 15 provided with heads 16 and 17, the latter of which is provided with a sleeve-like hub 18. To rigidly support the shell 15 from the motor housing 12, a tube or pipe section 19 is rigidly connected to the hub of the housing 12 and is extended through the head 16 and rigidly secured within the hub 18 of head 17 by suitable means such as a set-screw 20. A long sleeve 21 is telescoped onto the extended end of the pipe section 19 and its threaded end is extended through the head 16 and connected to said head by a packed nut 22.

The head 17 is flanged and is detachably connected to a supplemental head 23 by a packed joint 24 and machine screws 25. Head 17 and supplemental head 23 are spaced to form a pump chamber 26 which has an axial intake port 27 formed in said supplemental head 23. Head 17 is provided with circumferentially spaced main fluid outlet passages in the nature of ports 28.

At its delivery end casing 15 is provided with an outlet pipe 29. Located within the casing of the filtering chamber 15 and rigidly secured to the sleeve 21 is a pair of concentrically spaced conical screens 30 and 31 between which is contained the fibrous filtering material 32. These screens and the filtering material afford a conical partition between the receiving and the discharging end of the filtering chamber afforded by the casing 15.

It should now be noted that the motor-driven shaft 14 is axially extended through and journaled in the head 17 and projects into the pump chamber 26.

In the drawings the screens 30 and 31 are perforated thin sheet metal cones, but may take other forms. Their oblique extension within the casing 15 gives a maximum perforated surface 40 within the space allotted for the same.

The centrifugally acting pump head is located within the casing of the pump chamber 26 and is secured to the inwardly projected end of the motor-driven power shaft 14. This pump head is a hollow shell-like structure having an axial intake passage and open at its periphery for the free discharge of the circulated water or liquid under the action of centrifugal force. The pump head may take various forms but is preferably of

50 the form shown in Figs. 3 and 4 wherein the said pump head is made up chiefly of two reversely bulged discs or plates 33 and 34, the peripheries of which are brought close together but slightly spaced. The reduced nut-equipped end or trunnion of the shaft 14 is extended axially through

the inner disc 34 and is thus rigidly secured to said shaft for rotation therewith. The outside disc 33 has a quite large axial intake port 35 that registers with the intake port 27. A sealing ring or washer 36, preferably of fiber, is seated in the supplemental head 23 and has frictional engagement with the bulged side of the disc 33 surrounding the intake port 35 of the latter.

Located within the rotary head and secured to at least one of the discs thereof are substantially radial impelling vanes 37 that start radially inward of the intake port 35 and extend to or substantially to the periphery of the pump head. These vanes 37 may be spot welded or otherwise secured to both of the discs of the head. As best shown in Fig. 4, the disc 34 is provided with several circumferentially spaced ears 38 that are bent over and welded or otherwise secured to the overlapped edge of the disc 33. Here it should be noted that the circumferentially spaced ports 28 in the head or wall 17 of the pump chamber are located radially inward of the substantially cylindrical surrounding peripheral wall of the chamber 26, this being done for a purpose which will presently more fully appear.

The pump chamber 26, at at least one point and preferably at the extreme bottom thereof, is provided with a transverse intercepting groove or trough 39 from which outwardly extends a sediment discharge passage in the nature of a port 40. The term "sediment" is herein used to include solid or heavy foreign portions which, under the action of gravity, would naturally settle and which, under the action of centrifugal force, will be thrown radially outward against the surrounding cylindrical wall of the pump chamber.

As will hereinafter more fully appear, this rotary centrifugal pump mechanism operates as a combined pump and separator for removing the heavy or solid portions, called "sediment," from the water or other liquid that is being circulated by the pump and discharged through the filter. In this connection, it is important to note that the minimum open area of the foreign substance discharge passage formed in part by the port 40 is greatly less than the passages formed by the main fluid outlet ports 28 taken singularly or collectively, so that centrifugal separation can be automatically accomplished without materially reducing the flow through the main outlet passage or passages 28.

In Figs. 5 and 6 I have illustrated a somewhat modified form of the rotary pump head, the same, in this instance, being made up of a concavo-convex plate 41 secured to a hub 42, and a flat disc 43. In this arrangement the discs and plates are spaced at their peripheries, except for clinched ears 44 of the plate 41 that are bent over and hold the plate 43 in place. The hub 42 is adapted to be secured to the inner end of the power-driven shaft 14. This pump head, shown in Figs. 5 and 6, will have the inner propelling vanes 45 arranged like the vanes 37 of the previously described head.

In the operation of the combined pump and separator described, the water or fluid will be delivered through the port 27 into the interior of the rotary pump head and, under the action of centrifugal force, will be discharged from the periphery of the head under high velocity against the surrounding cylindrical wall of the chamber 26 and will be caused to rotate within said chamber in the direction in which the pump head is rotated. Under this action the heavier particles or sediment will be caused to closely hug or travel

against the interior cylindrical wall of the chamber and on reaching the intercepting trough or channel 39 will be stopped or intercepted in its movement and, under the internal pressure of the fluid, will be caused to escape or be discharged through the port 40.

The internal fluid pressure produced in the chamber 26 will cause the liquid, except for its discharge sediment and some slight leakage with the latter, to flow through the ports 28 to the interior of the conical shell 30, from thence through the filtering material, thence through the screen 31, and from thence out through the outlet or pipe 29. With the main fluid outlet ports 28 located as described, the sediment and the fluid that carries the same will be caused to circulate radially outward of said ports 28, thereby preventing the sediment from being discharged through ports 28 and causing the same to be skimmed off and discharged through the sediment port 40. By this arrangement the major portion of the sediment or impurities carried by the fluid will be removed therefrom before the fluid is subjected to the filter and only a very minor portion of the separation of impurities from the fluid will be intercepted by the filtering material. Hence, only infrequently will the filtering material require cleaning and when the filtering material does require cleaning it, with the screens 30 and 31, may be removed with the sleeve 21 simply by removing the head 16.

Attention could be further called to the fact that the fluid forced or drawn into the interior of the centrifugal head passes into the interior of said head through the port 35 radially inward of the vanes 37 and commingles in a common body before it is acted upon by the said vanes. This insures even distribution of the fluid between the circumferentially spaced vanes with resulting uniform discharge of the water or fluid at the periphery of the head.

In the application of this invention to a washer of the character described in my above identified pending application, the following additional connections may be employed and in the drawings are shown, to wit: The intake port 27 is connected to a tubular arm 47 that is provided, at its free end, with a screen-equipped receiving head 48. The outlet port or pipe 29, by a tube 49, is connected to a valve 50 from which a flexible discharge tube 51 is extended. The sediment discharge port 40 is connected to a tube 52, the end of which is arranged to discharge into the sediment trough 18.

What I claim is:

1. In a device of the kind described, a pump chamber having an axial intake port, a power driven shaft extending into said pump chamber through one wall thereof and in axial alignment with the intake port thereof, the inner periphery of said pump chamber being defined by a substantially cylindrical wall having a normally open peripheral discharge port for discharge of foreign substance and which has a diameter materially less than the width of the inner cylindrical surface of the pump chamber, the inner cylindrical surface of the peripheral wall of the pump chamber having a catch channel extending transversely thereacross and intersecting the said discharge port, a main fluid discharge port from the pump chamber in materially radially inwardly spaced relation from the peripheral wall of the pump chamber, and a rotary pump head mounted on said shaft within the pump chamber and having impelling vanes.

2. In a device of the kind described, a pump chamber having an axial intake port, a power driven shaft extending into said pump chamber through one wall thereof and in axial alignment with the intake port thereof, the inner periphery of said pump chamber being defined by a substantially cylindrical wall having a normally open peripheral discharge port for discharge of foreign substance and which has a diameter materially less than the width of the inner cylindrical surface of the pump chamber, the inner cylindrical surface of the peripheral wall of the pump chamber having a catch channel extending transversely thereacross and intersecting the said discharge port, a main fluid discharge port from the pump chamber, and a rotary pump head mounted on said shaft within the pump chamber and having impelling vanes, said pump head being a hollow structure composed of axially spaced walls, one of which is provided with an axial intake port in alignment with the intake port of the pump chamber.

3. The structure defined in claim 1 in which the said pump head is a hollow structure composed of axially spaced walls, one of which is provided with an axial intake port in alignment with the intake port of the pump chamber.

4. In a device of the kind described, a substantially cylindrical pump chamber having an axial intake port through one of its axially spaced walls, a filter chamber in axial alignment with the pump chamber and having one of its end walls formed by the other of the axially spaced walls of the pump chamber, a power driven shaft extending axially through the filter chamber and into the pump chamber, a rotary impeller head mounted fast on said shaft within the pump chamber, a normally open restricted discharge port for foreign substance in the peripheral wall of the pump chamber, a main fluid outlet port leading from the pump chamber to the filter chamber through the wall of the pump chamber separating the same from the filter chamber, said main fluid outlet port being materially radially inwardly spaced from the aforesaid restricted peripheral discharge port, a fluid outlet passage from the filter chamber, and a filter within the filter chamber interposed between the said main fluid outlet port leading from the pump chamber thereinto and the said outlet port from the filter chamber, said filter being a stationary element.

5. In a device of the kind described, a pump chamber having an axial intake port, a power driven shaft extending into said pump chamber through one wall thereof and in axial alignment with the intake port thereof, the inner periphery of said pump chamber being defined by a substantially circular wall having a normally open peripheral discharge port for discharge of foreign substance and which has a diameter materially less than the width of the inner circular surface of the pump chamber, a circumferentially spaced series of main fluid outlet ports leading from the pump chamber in materially radially inwardly spaced relation from the peripheral wall of the pump chamber, and a rotary pump head mounted on said shaft within the pump chamber and having impeller vanes.

6. The structure defined in claim 5 in which the inner substantially circular surface of the peripheral wall of the pump chamber is formed to provide a catch channel extending transversely thereacross and intersecting the foreign substance discharge port.

7. The structure defined in claim 5 in which the said circumferentially spaced main fluid outlet ports extend through a side wall of the pump chamber, and in further combination with a filter chamber in axial alignment with the pump chamber and having one of its walls formed by the discharge port-containing side wall of the pump chamber, the said power driven shaft extending through said wall and through said filter chamber, a fluid outlet passage from the filter chamber interposed between said circumferentially spaced main pump chamber outlet ports and the outlet from the filter chamber, and an annular stationary filter element in said filter chamber between the said circumferentially spaced outlet ports from the pump chamber and the outlet from the filter chamber.

8. In a device of the class described, a pump chamber defined by spaced side walls and an approximately circular peripheral wall, a substantially axial intake port in one of said side walls, a drum-like casing extending axially from the last said pump chamber wall, said drum-like casing having a closed end opposite said pump chamber wall, a tube rigidly carried by and projecting from the last said pump chamber wall through the closed end of said drum-like casing, a power driven shaft extending through said tube and the said wall of the pump chamber, a pump rotor mounted on said shaft within the pump chamber, a restricted normally open foreign substance discharge port through the peripheral wall of the pump chamber, a plurality of circumferentially spaced main fluid discharge passages from the pump chamber through the said pump chamber wall adjacent the said drum-like casing, said main fluid discharge passages being materially radially inwardly spaced from the peripheral wall of the pump chamber, a fluid outlet from the drum-like casing, and an annular filter disposed in said drum-like casing intermediate said pump chamber outlet ports and the said outlet passage from the drum-like casing.

9. In a device of the kind described, a pump chamber having an axial intake port, a power driven shaft extending into said pump chamber through one end wall thereof and in axial alignment with the intake port thereof, the inner periphery of the pump chamber being defined by a circular wall having a normally open peripheral discharge passage for discharge of foreign substance and which has a diameter materially less than the width of the inner peripheral surface of the pump chamber, a fluid outlet port leading axially through the other end wall of the pump chamber in materially radially inwardly spaced relation from the peripheral wall of the pump chamber, and a rotary pump head mounted on the shaft within the pump chamber and having impeller vanes.

VICTOR N. ALBERTSON.
